COMBINATION CLOSURE CAP AND DISPENSER

Irving L. Rabb, Saugatuck, Conn.

Application May 2, 1957, Serial No. 45,984

Term of patent 14 years

(Cl. D58—26)

Fig. 1.

Fig. 2.

Fig. 3.

Fig. 4.

Fig. 1 is a front elevational view of a combination closure cap and dispenser showing my new design;

Fig. 2 is a top plan view;

Fig. 3 is a bottom plan view; and

Fig. 4 is a front perspective view.

I claim:

The ornamental design for a combination closure cap and dispenser, substantially as shown.
